CLAIM

The ornamental design for a handle for an attache case and posts therefor, as shown and described.

DESCRIPTION

FIG. 1 is a perspective view of a handle for an attache case and posts therefor showing my new design;

FIG. 2 is a top plan view thereof;

FIG. 3 is a front elevational view thereof, the rear being identical;

FIG. 4 is a bottom plan view thereof; and

FIG. 5 is a right side elevational view thereof, and is identical to a left side elevational view thereof.
